UNITED STATES PATENT OFFICE

2,620,805

CIGARETTE EXTINGUISHER

Woodfin Grady Page, Orlando, Fla., and
Lee M. Page, Opp, Ala.

Application May 23, 1950, Serial No. 163,714

1 Claim. (Cl. 131—256)

1

This invention relates to means for extinguishing lighted cigarettes and for receiving same after being extinguished.

A primary object of the invention is to provide a cigarette extinguisher by means of which the lighted end of a cigarette is caused to come into direct contact with a liquid immersed surface for quick and certain extinguishing thereof and on slight pressure application thereto.

A further object of the invention is to provide a cigarette extinguisher embodying a rectangular casing having a liquid receptacle therein and an elongated cigarette extinguishing roll or mass of felt yieldably supported and guided in the receptacle relative to an opening in the top wall thereof.

Another object of the invention is to provide a receptacle having a spring supported cigarette extinguisher which is partially immersed in water in the receptacle and wherein the extinguisher is removably retained in operative position by a removable clean-out plug in the bottom wall of the receptacle with which it is removable from the receptacle.

A still further object of the invention is to provide a cigarette extinguisher which is self cleaning and having an adjacent self-closing receiver, the structure providing greater ease in disposing of used cigarettes and also having a pocket for supporting a pack of matches or the like for ready use.

Other objects and advantages of the invention will become apparent in the course of the following detailed description, taken in connection with the accompanying drawing, wherein—

Fig. 1 is a vertical sectional view in the plane of line 1—1 on Fig. 3, and showing the invention in accordance with a preferred structure embodiment thereof;

Fig. 2 is a horizontal sectional view in the plane of line 2—2 on Fig. 1;

Fig. 3 is a top plan view on a smaller scale;

Fig. 4 is a fragmental vertical section corresponding to the left hand end of Fig. 1 but taken in the plane of line 4—4 on Fig. 2.

Referring to the drawing, 10 designates a casing which may be constructed of any suitable material and which includes a relatively thick base 11, opposite side walls 12 and 13 and opposite end walls 14 and 15. The casing is shown as further including a cover or top member 16. This cover or top member need not be removable in the operation of the device however due to the removability of the extinguishing means through the bottom or base wall 11, as will later

2

appear. The two-part construction as shown would nevertheless aid in the assembly of the several parts as well as the repair of the device in use. It is proposed, therefore, that the top wall or cover member 16 be formed with a tight fitting flange 16a which provides a liquid seal with the side and end walls of the casing. This flanged cover construction may, however, be omitted and in place thereof the casing may be provided with a top wall integral with the side and end walls, very much as shown at the bottom 11 of the casing.

The casing further includes a partition 17 which divides the interior of the casing into a liquid receptacle 18 and a larger stub disposal receptacle 19, the latter having a self-closing lid.

Means are disposed within the receptacle 18 and adjacent an opening therein for extinguishing cigarettes and the same embodies a vertically disposed tubular guide frame 20. The frame 20 is of open construction for the free admission of water or other liquid from the receptacle 18 into the interior of the frame. Accordingly, the frame may embody a plurality (preferably four) 25 of bars 21 which are disposed as shown in Fig. 2 and which define slots therebetween. The upper ends of the bars 21 are preferably rigid with a ring 23 as a reinforcement for the otherwise free ends of the bars, and the upper edge of ring 23 is provided with inwardly directed stop lugs or flange 24. A spacing ring 24' is disposed within the ring 23 and beneath the flange 24.

The cover 16 is provided with a cigarette end receiving opening 25 and the base 11 immediately below this opening is provided with a threaded aperture 26 which normally receives a plug 27 having a flange 28 for seating engagement with a washer 29. The plug is preferably provided with a tool receiving and operating kerf 30. The lower ends of bars 21 are rigid with a ring 22 threadedly engaged with plug 27 so as to be removable therewith. The axes of the apertures 25 and 26 are coincident with that of frame 20.

Disposed within the guide frame 20 for vertical movement therein is a felt retainer and piston 31 which is of cylindrical form, having a centrally apertured bottom 32 and an open top 33 which is enlarged as at 33' for engagement with the spacing ring 24' under the lugs 24. The retainer is also of open construction to freely admit liquid to the interior thereof and accordingly its side wall is provided with circumferentially spaced vertical slots 34.

A tube 35 extends axially of the retainer 31 and which communicates with the central open-

ing in the bottom 32 and extends to the upper end of a mass of felt 36 disposed within the retainer. The tube 35 may be merely a bore through the mass material for aiding saturation of the felt 36. A coiled compression spring 37 is disposed between plug 27 and the retainer base 32. The coiled spring 37 as shown acts to yieldably support and normally elevate the retainer 31 within the frame 20. This compression type spring is preferably connected at its lower end to the inner surface of the screw plug 27 so as to be removable therewith. The upper end of the spring thereof engages the pan-like bottom 32 of the felt retainer 31.

A cylindrical screen 38 is disposed around the guide frame 20 adjacent the lower end for a purpose later to appear. The casing base 11 is provided with a second removable plug 39 for removal of cigarette stubs from the receptacle 19 and the cover or top wall is provided with a second aperture 40 for the admission of extinguished cigarette stubs into the receptacle 19.

The aperture 40 is normally closed by a door 41 which is pivotally secured beneath the cover at 42 and which is provided with a downwardly inclined portion 43 to which one end of a spring 44 is secured. The opposite end of the spring is free for removal and replacement of the cover but the spring is under sufficient compression with the cover applied as in Fig. 1 for urging the door into its normally closed position. The spring, however, readily yields upon downward pressure on the door, as by the admission of a cigarette stub, so that the door assumes the dotted line position, in Fig. 1, when pressure is exerted thereon.

The front wall 12 of the casing may be provided with a suitable pocket 45 for receiving a book of matches or the like, and the casing may be provided with suitable means for removably securing same to either a horizontal or vertical surface.

In operation of the structure above described water, or other suitable liquid is admitted to the receptacle 18 which may readily be accomplished by pressing down on the extinguisher retainer and piston 31 and pouring in the liquid through aperture 25, preferably to a depth substantially above the lower end of the retainer when in raised normal position. As is indicated in Figs. 1 and 4, this upper end of the mass of felt 36 is preferably convex for effecting ready removal of ashes from the lighted ends of cigarettes and rendering same self-cleaning.

When it is desired to extinguish a lighted cigarette or cigar stub C, the same is positioned vertically in aperture 25 with the lighted end in engagement with the upper rounded end of the felt 36. The stub is then pushed downwardly depressing the felt and carrying the retainer with it. It will be noted that the felt is at all times moist due to the submergence of its lower end thereof in the liquid. However, upon moving the retainer downward (Fig. 4) the retainer 31 acts to force liquid upwardly through the bore of the tube 35 and over the upper rounded end of the felt. This fountain of water not only acts as a secondary aid in extinguishing the cigarette, but further acts to wash the ashes off the rounded top extinguishing surface of the felt and into the receptacle 18.

The ashes which are washed from the top of

the felt 36 find their way to the bottom of the receptacle 18 where they are held back by the screen 38 which filters the water admitted to the felt 36 carried in the tube 35. After extinguishing, a stub is pushed past the door 41 and through aperture 40 into receptacle 19.

When the receptacle 18 becomes ash laden, the plug 27 together with the guide frame and the retainer 31 are readily removed for cleaning and the cigarette stubs may be removed in like manner from receptacle 19 upon removing the plug 39.

While we have disclosed our invention in accordance with a single structural embodiment thereof, such is to be considered as illustrative only, and not restrictive, the scope of the invention being defined in the sub-joined claim.

What we claim and desire to secure by United States Letters Patent is:

A cigarette extinguisher comprising a housing having side, top and bottom walls defining a water storage compartment having aligned openings in said top and bottom walls, a plug detachably closing the bottom wall opening, a tubular guide frame member mounted on and extending upwardly from said plug to a point immediately below the top wall opening, a tubular wall of forminous material closely surrounding said tubular guide frame member, a spring mounted on said plug and extending upwardly within said guide frame member, a piston mounted on the spring in reciprocable relation to said guide frame member, said piston having a bottom wall provided with an opening, and a liquid absorbing element mounted on said piston and movable therewith relative to said top wall opening, said absorbent element having a vertical opening extending therethrough and communicating with the opening in said piston, whereby when said element is manipulated through the top wall opening to move the piston downwardly within said guide frame member, liquid stored therebelow will be forced upwardly through said absorbent element to flow thereover and return to said compartment.
